PACKAGE WRAPPING APPARATUS

James M. Sutton, Long Beach, Calif.

Application November 1, 1949, Serial No. 124,880

17 Claims. (Cl. 53—149)

1

This invention relates to package wrapping machinery; more particularly it relates to a machine for completing the wrapping of a package partly wrapped before reaching the machine.

It is an object of this invention to provide an improved machine of this character.

It is another object of this invention to provide a package wrapping machine which performs only some of the required operations in applying the wrapper, thereby simplifying and reducing the cost of the machine.

It is another object of this invention to provide a package wrapping machine wherein the wrappers are initially applied manually or otherwise before the packages reach the machine which completes the wrapping.

It is another object of this invention to provide a package wrapping machine wherein the initial and simple steps of applying the wrappers are performed before the packages reach the machine, the machine performing the subsequent and more difficult step of applying the wrapping.

It is another object of this invention to provide a package wrapping machine having novel means for closing the ends of the wrapper.

It is still another object of this invention to provide a package wrapping machine which is readily adjustable to accommodate packages of different sizes.

This invention possesses many other advantages and has other objects which may be made more easily apparent from a consideration of several embodiments of the invention. For this purpose there are shown several forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

In the accompanying drawings:

Figure 1 is a side elevation of a package wrapping machine incorporating the features of the invention;

Figure 2 is a detail section taken substantially as indicated by lines 2—2 of Figure 1;

Figure 3 is a detail section taken substantially as indicated by line 3—3 of Figure 2;

Figure 4 is a transverse section taken substantially as indicated by line 4—4 of Figure 1;

Figure 5 is a fragmentary longitudinal section on an enlarged scale, taken substantially as indicated by line 5—5 of Figure 4;

Figures 6, 7 and 8 are detail sections taken

2

substantially as indicated by the correspondingly numbered lines on Figure 5;

Figures 9 and 10 are views similar to Figure 5, but showing different operating positions of the parts;

Figures 11, 12, 13 and 14 are detail sections on an enlarged scale, taken substantially as indicated by the correspondingly numbered lines of Figure 10;

Figures 15, 16, 17 and 18 are fragmentary perspective views illustrating successive steps performed by the machine on the wrapper;

Figure 19 is a detail transverse section taken substantially as indicated by line 19—19 of Figure 1;

Figure 20 is a fragmentary section, taken substantially as indicated by line 20—20 of Figure 19;

Figure 21 is a view similar to Figure 8, but showing a modified form of the machine; and

Figure 22 is a section taken substantially as indicated by line 22—22 of Figure 21.

As shown, the machine operates to complete the wrapping of flat elongated packages, such as indicated by the letter P having a substantially rectangular cross section. Each package P before reaching the machine is wrapped in a transversely extending sheet of suitable plastic material such for example as "Cellophane" which will adhere in response to heat and pressure. This wrapper W is overlapped at 4 to provide a seam extending lengthwise of one face of the package P and projects beyond the opposite ends of the package. Thus, Figure 15 shows one end of the package P with the projecting wrapper W, and it is to be understood that the wrapper projects similarly beyond the opposite end. Further, all operations by the machine are substantially identically and simultaneously performed on both ends of the package P.

The machine includes a moving carrier 6 for advancing the packages P to cause successive operations to be performed on the wrapper W, a plurality of flights 7 being provided on the carrier 6, for engaging the respective packages P. Means are associated with each flight so that when the package P is placed on the flight by the operator, that portion 2 of the wrapper which projects from the trailing edge of the package P is folded in, as shown in Figure 16. Subsequent advance thereafter causes the package to advance between a pair of stationary plate like elements 8 which operate to cause successively the wrapper portion 3 projecting from the leading edge of the package to be folded in, as shown in Figure

17, the bottom projecting portion 4 to be folded

up, Figures 11 and 12, and the top projecting portion 3 to be folded down thereover, Figures 13, 14 and 18. The folding of the wrapper projections 4 and 5, lifts the package P from the flight 7 to a short track T which diverts the package from the carrier, and in which the package continues to advance under the influence of a projecting portion of the flight 7 and then under the influence of a swingable arm structure 8. At the end of the track T, a heater H is arranged to apply heat to the ends and bottom of the package P, causing the overlapped portions of the wrapper W to adhere. The movement of the arm structure 8 is arranged to provide a period of dwell for the package P on the heater H and then to eject the package for further disposition, as for example to a ramp 9 for movement by gravity to a conveyor 10.

Referring in detail to the drawings, the machine comprises a frame 12 formed of a fixed section 12-a and a relatively movable section 12-b having respectively table like top members 13-a and 13-b. The frame sections 12-a and 12-b are guided for movement toward and away from each other by the aid of transverse guide bars 14 secured respectively adjacent the forward and rear edges of one of the top members, as 13-a, and confined respectively between pairs of plates 15 secured to the other top member 13-b by the angle clip 16. The pairs of plates 15 confine the bars 14 laterally, and have rollers 17 between them for restraining the bars vertically. The means for adjusting the movable frame section 12-b will be described hereinafter (see Figures 2 and 3).

The carrier 6 comprises a pair of circular opposed members 20 and 21 mounted on a tubular shaft 22 rotatably supported on the frame 12 by bearings 23 and 24 secured respectively to the under-side of the frame top members 13-a and 13-b (see Figure 6). The shaft 22 has a reduced portion providing a shoulder 22-a, and a collar 25, between which the bearing 23 is confined, thus preventing axial movement of the shaft 22 relative to the top member 13-a. The shaft 22 is freely slideable in the bearing 24. The member 20 is fixed on the shaft 22 by means of a pin 26, the other member 21 being secured to rotate with the shaft 22 but free to move axially thereon, by means of a pin 27 passing through opposed slots 22-b in the shaft 22 (see also Figures 5 and 9).

As will appear hereinafter, the member 21 must be maintained in fixed axial relation with the movable frame section 12-b. For this purpose, the frame top member 13-b and the member 21 are connected in spaced relation by the aid of a threaded adjusting rod 28 adapted to telescope within the shaft 22, engaging a threaded bushing 29 fixed in the open end of the shaft 22. The inner end of the rod 28 has a head 30 secured thereon for rotation relative to the rod 28 and engaged by pin 27. Thus, the axial position of the member 21 is determined by the position of the rod 28, which may be rotated independently of the shaft 22 by means of knob 31, but normally rotates with the shaft 22 due to the frictional grip of bushing 29.

The outer end of the rod 28 is rotatably supported by a bearing bracket 32 secured to the frame top member 13-b and which is confined between shoulders 28-a and 28-b on the rod 28. In this manner, the rotatable member 21 and the movable frame section 12-b including the top member 13-b are maintained in fixed axial relation for all adjusted positions of the frame sec-

tion 12-b. Appropriate rotation of rod 28 with respect to shaft 22 as by knob 31, will alter the spacing between the carrier members 20 and 21.

Each of the flights 7 comprises narrow arcuate strips 36 and 37 of limited angular extent, mounted respectively on the inside faces of the members 20 and 21 by the aid of angle clips 38 each having an intermediate offset 38-a, in opposed aligned relation. The outer surface of the strips 36 and 37 is substantially flush with the periphery of the members 20 and 21, the trailing ends of the strips being formed to provide radial extensions as 37-a to support and engage a package P on the respective strips 36 and 37 for advance with the rotating members 20 and 21.

Arms 40 and 41 are respectively pivotally mounted on the inner faces of the members 20 and 21 by the aid of short pintles 42 and 43 which extend respectively through the members 20 and 21 at points spaced radially inwardly from the trailing ends of strips 36 and 37. The arms 40 and 41 have forwardly projecting fingers 44 and 45 respectively at their outer ends and are each urged counterclockwise about their pivots by tension springs, one of which is shown at 47, to engage the said ends of strips 36 and 37. In this position the fingers 44 and 45 extend forwardly of the corresponding radial extensions 37-a (see Figures 7 and 9).

The width of these fingers 44 and 45 is slightly less than the thickness of the package P and the spacing of the rotatable members 20 and 21 is so adjusted by the previously described means that opposite pairs of fingers 44 and 45 are separated by a distance slightly greater than the length of the package P. The arrangement is such that when a partly wrapped package P (Figure 15) is placed on a flight 7 by the operator, that portion 2 of the wrapper W projecting beyond the end of the trailing edge engages the finger 44 and is folded inwardly against the end of the package P as shown in Figure 16. The wrapper portion projecting beyond the opposite end at the same time engages the opposite finger 45 and is similarly folded inwardly.

To enable the fingers 44 and 45 to pass the plate like elements F which perform the subsequent folding operations, means are provided to swing the arms 40 and 41 to a position clearing the elements F during an appropriate part of the rotation of the members 20 and 21. For this purpose, operating arms 48 and 49 are mounted respectively on the pintles 42 and 43 on the outside of the members 20 and 21 and are provided with rollers 50 and 51 at their outer ends engageable with stationary cam means 52 and 53, supported by supplemental frames 54 and 55 on the frame top members 13-a and 13-b.

The arrangement is such that the fingers 44 and 45 are normally projected in their operating position, but upon reaching a predetermined point in the rotation of the members 20 and 21 are retracted to pass the elements F by an engagement of the rollers 50 and 51 with the cam means 52 and 53 (see Figure 10), the cam means being so formed as to allow the fingers 44 and 45 to return to their normal positions under the influence of springs 47 after passing the elements F.

The element F comprises a pair of opposed plates 60 and 61, substantially identical, except being of opposite hand and mounted respectively on the supplemental frames 54 and 55, so that adjustment of the carrier 6 to accommodate a particular length of package will correspondingly space the plates 60 and 61. The plates 60 and 61

have projecting fingers 62 and 63 respectively, the finger 62 engaging the wrapper projection 3 from the leading edge of the package and folding it inwardly against the package end as the package is advanced by the carrier 6 (see Figure 17). The finger 63 similarly folds the corresponding portion of the wrapper against the opposite end of the package.

The wrapper W now has the projecting portions 4 and 5 at one end and corresponding projecting portions at the other end which lie substantially in the direction of advance. For accommodating and folding these portions the plates 60 and 61 are each provided with a pair of through slots 64 and 65 with oppositely inclined portions. Thus, the slot 64 has a substantially horizontal portion 64-a for accommodating the upper wrapper projection 4 without bending or folding, the slot 65 which accommodates the lower wrapper projection 5 inclining upwardly so that as the package is advanced, the lower projection 5 is folded upwardly against the end of the package (see Figures 11 and 12). In this connection it is to be noted that the amount of wrapper projection 5 is such that at the completion of the fold the projection is entirely free of the slot 65. Adjacent the termination of slot 65, the slot 64 is inclined downwardly and similarly folds, the upper wrapper projection 4 is folded downwardly against the end of the package (see Figures 13 and 14).

The horizontal slot portion 64-a diverges slightly from the path of the package on the carrier flight 1. Thus, the package is lifted as it advances, so that the leading edge engages the track forming members 66, 67, mounted respectively on the plates 60 and 61, and the package is diverted from the carrier. To restrain and guide the package during the initial part of the folding operations by the plates 60 and 61, horizontally directed guide members 68 and 69 are provided respectively on the plates, each being adjustably secured by a single screw 70 and 71.

As clearly shown in Figure 10, the package, after a short advance on the track 66, 67, moves out of contact with the flight projections 37-a, supplemental means comprising the swingable arm structure 8 being provided for continuing the advance.

Referring particularly to Figures 1, 4 and 19, the arm structure 8 comprises a pair of arms 8-a and 8-b carrying small rollers 8-c at their outer ends for engaging the package P. The arms 8-a and 8-b are so positioned that the package is engaged adjacent its opposite ends, and secured in fixed axial relation with respect to the stationary and movable frame sections 12-a and 12-b. Thus, adjustment of the machine for different sizes of packages causes corresponding adjustment of the arm structure.

The arms 8-a and 8-b are supported for swinging movement by the aid of a square shaft 73, one end of which has a circular extension 73-a rotatably supported by a post 74 on the frame 54 which in turn is mounted on the fixed frame section 12-a, the shaft 73 being restrained against axial movement in the post 74 by the nuts 75 and the hub of operating lever 77 fixed on the shaft, suitable washers being interposed to reduce friction. The other end of the shaft 73 is supported for axial as well as rotary movement in post 75 by a bushing 75-a.

The arm 8-a is fixed on the shaft 73 as by a set screw 72, the arm 8-b being splined on the shaft 73 by means of a square tube 73-b, main-

tained in axially fixed relation with post 75 by means of a flange 73-c engaged by a retaining lug 75-b on the post 75. In this way, arm 8-b is constrained to move with post 75 on the adjustable frame section 12-b, the arm 8-a being maintained in fixed axial relation with post 74 on the stationary frame section 12-a.

As best shown in Figures 1, 4 and 11, the plate 61 is mounted on the supplemental frame 55 by the aid of an angle bar 78 which is slidably supported for horizontal adjustment on a pad 79 forming part of the frame 55. The plate 61 is secured in spaced relation to the bar 80 as by rods 82, the bar 78 being secured in adjusted position on the pad 79 as by a thumb screw 83. The opposing plate 60 is secured to the supplemental frame 55 in a substantially identical manner by angle bar 80 and pad 81. Thus, plates corresponding with plates 60 and 61 but adapted for packages of a different cross section may be readily substituted.

Heating means H are arranged to provide a continuation of the track 66, 67 as well as of the plates 60 and 61 for sealing the overlapped portions of the wrapper before the packages P leave the machine. Thus, referring to Figures 1, 5 and 8, the means H comprises a rectangular bar 91 in which a pair of conventional electric heating elements 92 and 93 are incorporated. The bar 91 is fixed to the stationary frame 54 by the aid of bracket 94, and is slidably supported on the movable frame 55 by the aid of a grooved bracket 95 engaging a tongue 91-a on the bottom of the bar 91, the upper surface of the bar 91 forming a continuation of the track 66, 67. That end of bar 91 adjacent the fixed frame 54 has an upward extension 96 in good heat transfer relation with the bar, the inner face of which forms a continuation of the plate 60 for engaging one end of the package P. A member 97 is supported on the movable frame 55 as by a bracket 98 closely spaced above the bar 91 so as to be in good heat receiving relation therewith, the inner face of the member 97 forming a continuation of the plate 61 for engaging the other end of the package P.

Guide rails 100 and 101 are mounted respectively on plates 60 and 61 above the track elements 66 and 67, the lower faces thereof engaging the packages and maintaining them on the track elements and in contact with the heater 91. The rails 100 and 101 are adjustable toward and away from the track elements. Thus, as shown in Figure 5, rail 101 is pivotally secured at 101-a to frame 61 and is maintained in angularly adjusted position by a screw 101-b threaded into frame 61 and engaging a clearance slot 101-c in the rail. The rail 100 is similarly adjustable.

To enable the heat to more effectively adhere to the overlapped portions of the wrapper, it is desirable that the period of contact with the heated surfaces of the members 91, 96 and 97 be slightly prolonged. Accordingly, the arm structure 8 is operated to advance the package onto these surfaces and provide a period of dwell before further movement and final ejection from the machine.

For this purpose, a plurality of cam means 105 are provided on the carrier member 20 as associated respectively with the flight 1, each of which comprises a roller 105-a, an arcuate surface 105-b and another roller 105-c (see Figures 1 and 4).

The previously mentioned lever 77 has a slot 77-a engaging a pin 106-a at the upper end of

a lever 106 pivotally mounted at 107 on the post 74 and having a slot 106-b at its lower end engaged in turn by a pin 108-a at the upper end of lever 108, pivoted at 109 on the post 74 and having a lower extension 108-b for engaging the same means 105. A tension spring 110 connected between the frame 54 and lever 108 serves to maintain lever 106 against a stop 103 with arms 8 positioned to clear the package P as it leaves the carrier flight 7 (see also Figures 5 and 9).

Figure 1 shows the cam roller 105-a just engaging the lever extension 108-b, lever 108, arm 7, etc., being in their normal positions. Rotation of the carrier 6 causes the cam roller 105-a to swing lever 108 to the broken lines position "X" which in turn causes arms 8 to swing downwardly to the broken line position of Figure 10, and advance the package to the heater H. Continued rotation of the carrier 6 causes the end of the operating extension 108-b to ride over the roller 105-a onto the arcuate surface 105-b which maintains lever 108 and arms 8 in this position and allows the package to remain on the heater. Further rotation of the carrier 6 thereafter causes the roller 105-c to engage the lever extension 103-b moving it additionally to the broken line position Y and causing arms 8 to swing further to the left (Figure 5) and eject the package P. Thereafter the extension 108-b rides over the roller 105-c, and lever 108, arms 8, etc., return to their normal positions under the influence of spring 110.

The carrier 6 may be driven in any suitable manner, for example by a small motor 115 driving through suitable gearing, a friction roll 116 adapted to engage a peripheral band 117 on the rotatable carrier member 20. The motor 115 is pivotally mounted at 118 on the underside of the frame top member 13-a for optional movement by control linkage 114 to bring the friction roll 116 into and out of driving engagement with the member 20.

The operation of the machine may now be reviewed. The packages P have the wrappers W applied manually or otherwise, to extend transversely about the packages and project beyond the ends thereof, with an overlapped portion 1 extending longitudinally of one of the wide sides of the packages. The wrappers may be retained as by a spot of adhesive between the overlapped portions or by heating.

With the carrier 6 in operation, the prewrapped packages are placed by the operator on the successive flights 7 as they rise about the top frame members 13-a and 13-b with the overlapped portion 1 of the wrapper W faced inwardly and a narrow side against the flight extensions 37-a. This operation causes the fingers 44 and 45 to fold that portion of the wrapper 2 projecting beyond said side against the end of the package.

As the carrier 6 advances, the fingers 44 and 45 are retracted, and the package passes between the plates 60 and 61, the fixed fingers 62 and 63 of which fold that portion of the wrapper 3 projecting beyond the other narrow side against the end of the package. Those portions of the wrapper 4 and 5 projecting beyond the long sides of the package, then enter the slots 64 and 65 in the plates 60 and 61 and are folded thereby respectively downwardly and upwardly against the ends of the package 1. During this folding operation the package is diverted from the carrier flight 7 onto the track 66, 67 and is moved therealong by arm structure 8 onto the heater H, where it rests

a brief interval before ejection by further movement of the arms 8.

Although the machine has been shown and described as for operating with flat ended packages in which the ends extend in a direction normal to the sides, the tolerances are not close except between the heater plates 96 and 97. Thus, the machine is capable of use with packages comprising a prewrapped basket like container with flaring ends and reenforcing bead around its upper edges, such as shown at 119 in Figure 21, by applying adapter members 120 and 121 respectively to the heater plates 96 and 97 so that the folded ends of the wrapper will be closely confined therebetween. As shown in Figure 22, these members are of increased length in accordance with the size of the containers.

I claim:

1. In apparatus for closing the wrapper of a partly wrapped rectangular package, the wrapper, when the package is delivered to the apparatus, extending transversely about the package and projecting beyond the ends thereof: a movable carrier including a pair of opposed rotary members, frame supporting said members, opposed flights on said members, for supporting the package for sideward advance in the direction of a pair of the sides, arms on said members for engaging the packages on the flights, means on said arms and said frame respectively for folding those portions of wrapper projecting from the sides positioned transversely of the direction of advance against the package ends; means on said frame for thereafter successively folding those portions of the wrapper projecting from the first mentioned pair of sides against the package ends; means for removing the package from said carrier and for advancing it independently thereof; and means for causing said folded portions to adhere.

2. In apparatus for closing the wrapper of a partly wrapped rectangular package, the wrapper, when the package is delivered to the apparatus, extending transversely about the package and with an overlap extending longitudinally of one side thereof, said wrapper projecting beyond the ends of the package: a movable carrier including a pair of opposed rotary members, a frame supporting said members, means on said members for supporting the package for sideward advance in the direction of a pair of the sides, swingable arms on said members for engaging the packages; means on said arms and said frame respectively for folding those portions of the wrapper projecting from those sides positioned transversely of the direction of advance against the ends of the package; means on said frame for thereafter successively folding those portions of the wrapper projecting from the first mentioned pair of sides against the package ends; means for removing the package from said carrier and for advancing it independently thereof; and means for applying heat and pressure to said overlap and folded portions to cause them to adhere.

3. In apparatus for closing the wrapper of a partly wrapped rectangular package, the wrapper, when the package is delivered to the apparatus, extending transversely about the package with an overlap extending longitudinally of one side thereof, said wrapper projecting beyond the ends thereof: a movable carrier including a frame; opposed, circular members mounted for rotation on said frame, package engaging means on said members for supporting said package for

sideward advance in the direction of a pair of the sides; means on said frame folding portions of the wrapper projecting from the sides positioned transversely of the direction of advance against the package ends; a pair of fixed members on said frame respectively engaging the opposite ends of said package and having respectively continuous slots with oppositely inclined portions for accommodating and successively folding those portions of the wrapper projecting from the first mentioned pair of sides against the package ends; a track fixed to and extending between said fixed members, means for removing the package from said carrier and advancing it on said track; and means in the path of packages moving on said track for causing said overlap and said folded portions to adhere.

4. In apparatus for closing the wrapper of a partly wrapped rectangular package, the wrapper, when the package is delivered to the apparatus, extending transversely about the package with an overlap extending longitudinally of one side thereof, said wrapper projecting beyond the ends of the package: a movable carrier including a frame, a pair of opposed members mounted for rotation about a horizontal axis on said frame, package engaging means supported on and between said members for supporting the package for sideward advance in the direction of a pair of the sides thereof, on said package engaging means; means for folding that portion of the wrapper extending from one side of the package against the end thereof independently of the advance of the package; means for folding that portion of the wrapper projecting from the opposite side of the package against the end thereof responsive to advance of the package; a pair of fixed members on said frame supporting the second mentioned folding means and respectively engaging the opposite ends of said package and having respectively continuous slots with oppositely inclined portions for accommodating and successively folding those portions of the wrapper projecting from the first mentioned pair of sides against the package ends, responsive to further advance of the package, a track associated with said fixed members for receiving packages from said rotary members; means for removing the package from said carrier and advancing it on said track; and means for causing said overlap and said folded portions to adhere.

5. In apparatus for closing the wrapper of a partly wrapped rectangular package, the wrapper, when the package is delivered to the apparatus, extending transversely about the package projecting beyond the ends thereof: a movable carrier including a pair of opposed rotary members, a frame supporting said members for rotation thereon, package engaging members on said rotary members for supporting said package for sideward advance in the direction of a pair of the sides; means respectively connected with said frame and said rotary members for folding those portions of wrapper projecting from the sides positioned transversely of the direction of advance against the package ends; a pair of fixed members on said frame respectively engaging the opposite ends of said package and having respectively continuous slots with oppositely inclined portions for accommodating and successively folding those portions of the wrapper projecting from the first mentioned pair of sides against the package ends; means forming a stationary track cooperating with said fixed mem-

bers for diverting the package from the carrier; means operable responsive to rotation of said rotary members for advancing the package along said track between said fixed members; and means for causing said folded portions to adhere.

5 6. In apparatus for closing the wrapper of a partly wrapped rectangular package, the wrapper, when the package is delivered to the apparatus, extending transversely about the package with an overlap extending longitudinally of one side thereof, said wrapper projecting beyond the ends of the package: a frame, a movable carrier including a pair of opposed rotary members, means mounting said members for rotation on said frame, means on said rotary members for supporting said package for sideward advance in the direction of a pair of the sides; means carried by said frame and said rotary members for folding those portions of the wrapper projecting from those sides positioned transversely of the direction of advance against the ends of the package; a pair of fixed members on said frame respectively engaging the opposite ends of said package and having respectively continuous slots with oppositely inclined portions for accommodating and successively folding those portions of the wrapper projecting from the first mentioned pair of sides against the package ends; means on said frame forming a stationary track cooperating with said fixed members for diverting the package from said carrier; means providing a heated surface forming a continuation of said track as well as of said fixed members; and means actuated responsive to rotation of said rotary members for advancing the package along said track, and providing a period of dwell on said heated surface.

10 7. In apparatus for closing the wrapper of a partly wrapped rectangular package, the wrapper, when the package is delivered to the apparatus, extending transversely about the package and projecting beyond the ends of the package; a frame, a movable carrier including a pair of opposed rotary members, means mounting said members for rotation on said frame, means on said members for supporting said package for sideward advance in the direction of a pair of the sides thereof; means movably mounted on said members for folding that portion of the wrapper extending from the trailing side of the package against the end thereof in response to placement of the package on the carrier and independently of the advance of the package; fixed means on said frame for folding that portion of the wrapper projecting from the opposite side of the package against the end thereof responsive to advance of the package; means for retracting said movably mounted means to clear said fixed means in response to advance of the carrier and including a fixed cam means on said frame; means carried by said frame for thereafter folding those portions of the wrapper projecting from the first mentioned pair of sides against the package ends, responsive to further advance of the package; means on said frame for removing the package from said carrier and for advancing it independently thereof; and means on said frame for causing said folded portions to adhere.

15 8. In apparatus for closing the wrapper of a partly wrapped rectangular package, the wrapper, when the package is delivered to the apparatus, extending transversely about the package with an overlap extending longitudinally of one side thereof, said wrapper projecting beyond the ends of the package; a frame, a movable carrier

including a pair of opposed rotary members, means mounting said members for simultaneous rotary movement about a horizontal axis on said frame, package engaging means on said members for supporting said package for sideward advance in the direction of a pair of the sides; means on said frame and said members for folding those portions of the wrapper projecting from those sides positioned transversely of the direction of advance against the ends of the package; fixed means of said frame thereafter for successively folding those portions of the wrapper projecting from the first mentioned pair of sides against the package ends; means on said frame forming a stationary track cooperating with said fixed means for diverting the package from said carrier; means providing a heated surface forming a continuation of said track as well as of said fixed means; means for advancing the package along said track, and providing a period of dwell on said heated surface, comprising a swingably mounted arm on said frame having an actuating extension; and means on said rotary members engageable with said extension for actuating said arm in response to movement of the carrier.

9. In a package wrapping machine: a carrier for supporting and advancing the packages comprising a pair of spaced opposed rotatable members; opposed, aligned package engaging flights respectively on said members; a frame, a rotatable element on said frame mounting said members and secured in driving relation therewith; means for adjusting one of said members along said element with respect to the other member; and means respectively mounted on said members and said frame for engaging the ends of the package to perform a folding operation on the wrapper.

10. In a package wrapping machine: a carrier for supporting and advancing the package comprising a pair of spaced opposed rotatable members; opposed, aligned package engaging flights respectively on said members; a tubular element mounting said members and secured in driving relation therewith; one of said members being axially adjustable, a pair of opposed frames rotatably mounting said element; one of said frames being movable toward and away from the other frame, an adjusting member extending within said tubular element and secured in fixed axial relationship with one of said rotatable members but permitting relative rotation thereof; opposed means mounted on said frames for engaging the ends of the package carried thereto by said flights to perform a folding operation on the wrapper; means connecting said one frame with said adjusting member for movement with the adjusting member and means including a threaded connection between said tubular element and said adjusting member moving said one frame to vary the spacing of said rotatable members as well as the spacing of said flights, responsive to operation of said adjusting member.

11. In a package wrapping machine: means forming a frame comprising a fixed section and a relatively movable section connected thereto for movement toward and away therefrom; a carrier for supporting and advancing the packages comprising a pair of rotatable members; opposed, aligned package engaging flights respectively on said members; an element mounting said members and secured in driving relation therewith with one of said members axially adjustable thereon; means respectively on said

frame sections rotatably mounting said element, means securing one of said members in fixed axial relation with respect to the fixed frame section; means for engaging the ends of the package to perform a folding operation on the wrapper and including portions mounted respectively on said frame sections; and means for adjusting the movable frame section toward and away from the fixed section, including a connection for maintaining the other rotatable member in fixed axial relation with respect to the movable frame section.

12. In a package wrapping machine: means forming a frame comprising a fixed section and a relatively movable section connected thereto for movement toward and away therefrom; a carrier for supporting and advancing the packages comprising a pair of rotatable members; opposed, aligned package engaging flights respectively on said members; a tubular element mounting said members and secured in driving relation therewith; one of said rotatable members being axially adjustable on said element, means respectively on said frame sections rotatably mounting said element, the mounting means on the fixed frame section securing said element against axial movement with respect thereto; means securing the other said members in fixed axial relation with respect to said fixed frame section; means for engaging the ends of the package to perform a folding operation on the wrapper and including portions mounted respectively on said frame sections and said rotary members; and means for adjusting the movable frame section toward and away from the fixed section including a threaded rod in telescopic relation with said tubular element, and connected respectively to the movable frame section and to the axially adjustable rotatable member.

13. In a package wrapping machine: means forming a frame comprising a fixed section and a relatively movable section connected thereto for movement toward and away therefrom; a carrier for supporting and advancing the packages comprising a pair of rotatable members respectively in fixed axial relation with the frame sections; means in the path of movement of the packages for engaging the ends of the packages to perform a folding operation on the wrapper and including portions mounted respectively on said frame sections; track forming elements respectively on said frame sections cooperating to receive the packages from said carrier; heater means including spaced opposed elements respectively secured to said frame sections for engaging the ends of the packages; and means for moving the movable frame section toward and away from said fixed section.

14. In a package wrapping machine: a carrier for supporting and advancing the package comprising a pair of axially spaced rotatable members; means connecting said members in driving relation; a frame comprising a pair of opposed sections respectively supporting said members in fixed axial relation with respect to the sections; one of said sections being movable to vary the spacing between the sections, means on each of said sections in the path of the package for engaging the ends of the package to perform a folding operation on the wrapper, a track for receiving the package from the carrier; and a swingable arm structure for advancing the package along the track, said structure including a pair of arms oscillatable about an axis and se-

cured respectively in fixed axial relation with said frame sections.

15. In a package wrapping machine: a carrier for supporting and advancing the package comprising a pair of axially spaced rotatable members; means connecting said members in driving relation; a frame comprising a pair of opposed sections, one of said sections being movable to vary the spacing between said sections, means respectively supporting said members in fixed axial relation with respect to the sections; means on each section for engaging the ends of the package to perform a folding operation on the wrapper, a track for receiving the package from the carrier; and a swingable arm structure for advancing the package along the track, said structure including a shaft; means respectively on said frame sections oscillatably mounting said shaft; means on one of said mounting means securing said shaft in fixed axial relation therewith; a pair of arms in driving relation on said shaft; means securing one of said arms against axial movement on said shaft; and means securing the other arm in fixed axial relation with the other of said mounting means.

16. In a package wrapping machine: a carrier for supporting and advancing the package comprising a pair of axially spaced rotatable members; means connecting said members in driving relation; a frame comprising a pair of opposed sections, one of said sections being movable to vary the spacing between the sections, means respectively supporting said members in fixed axial relation with respect to the sections; means on each section for engaging the ends of the package to perform a folding operation on the wrapper, a track for receiving the package from the carrier; and a swingable arm structure for advancing the package along the track, said structure including a shaft; means respectively on said frame sections oscillatably mounting said shaft; means on one of said mounting means securing said shaft in fixed axial relation therewith; an arm axially secured on said shaft; a tubular element slidable on said shaft and in driv-

ing relation therewith; means securing said element in fixed axial relation with respect to the other of said mounting means; and an arm fixed on said element.

- 5 17. In a package wrapping machine: a pair of opposed frame sections, means connecting said sections for relative movement to vary the spacing therebetween, opposed means for supporting packages for advance in a given path being respectively mounted in fixed relation to said sections so that the space therebetween varies according to the spacing between said sections, a pair of opposed rotary members, each mounted on one of the sections and provided with 10 means for supporting and advancing the packages to said opposed means, other means supported by and between said sections for contacting said packages and advancing them on said opposed means, opposed means respectively connected with said sections subject to spacing according to the spacing between the sections and operable for performing folding operations on the wrappers for the packages and means for moving one section toward and away from 15 20 25 the other section to vary the spacing therebetween.

JAMES M. SUTTON.
